UNITED STATES PATENT OFFICE.

ALEXANDER H. MORROW, OF PITTSBURGH, PENNSYLVANIA.

HEATER OR BOILER.

1,312,801.

Specification of Letters Patent. Patented Aug. 12, 1919.

Application filed October 9, 1914. Serial No. 865,910.

To all whom it may concern:

Be it known that I, ALEXANDER H. MORROW, a citizen of the United States, residing at Pittsburgh, in the county of Allegheny and State of Pennsylvania, have invented a new and useful Improvement in Heaters or Boilers, of which the following is a full, clear, and exact description, reference being had to the accompanying drawings, forming part of this specification, in which—

Figure 1 is a vertical section taken on the line I—I of Figs. 2 and 3;

Fig. 2 is a horizontal section taken on the line II—II of Fig. 1;

Fig. 3 is a vertical section taken on the line III—III of Fig. 1;

Fig. 4 is a perspective view of one of the intermediate heater sections; and

Fig. 5 is a detail sectional view of the lower nipple connection.

My invention has relation to heaters or boilers of the sectional type, and which employ a fluid fuel, such as gas or oil. The object of my invention is to provide a heater or boiler of this general character, in which the sections are so constructed and related to each other as to provide not only for a maximum heating area, but also for a highly efficient and economical application of the fuel to heating surfaces and circulation of the products of combustion.

The nature of my invention will be best understood by reference to the accompanying drawings, in which I have shown a preferred embodiment, it being premised, however, that various changes may be made in the details of construction and arrangement of the parts, without departing from the spirit and scope of my invention as defined in the appended claims.

In these drawings, I have shown a heater or boiler composed of two end sections or units, and three intermediate sections or units; but it will be understood that the number of intermediate units may be varied according to the size and capacity of the heater.

The end sections or units 2 and 3 are counterparts, except that they are rights and lefts, each of them being in the form of a casting having a hollow web with a flat outer vertical face, forming one of the external walls of the heater, the inner face of each section being formed with alternating hollow projections 4 and recess portions 5.

The intermediate sections or units 6 are preferably all counterparts, each of them having a hollow central vertical web and their vertical faces formed with hollow horizontal alternating projecting portions 7, and recess portions 8, which are of generally similar form to those of the inner faces of the end sections. The recess and projecting portions of the intermediate units are, however, staggered with relation to the corresponding portions of the end sections and to the corresponding portions of the opposed surfaces of adjacent intermediate sections, so that when the sections are assembled, the projections of all of the sections will be in intercalated relation with the recess portions of adjacent sections. Each unit is also provided at one end with a vertical header 7^a which communicates with the hollow web and the horizontal projecting portions, the headers of the units forming the back of the boiler. The units are also each provided with a horizontal header 7^b which form the top of the boiler. All of the sections are preferably provided at the base with abutting flanges 9 and at their upper portions with abutting flanges 10. Each section is also formed at the lower end of the header with a tubular seat 11, to receive a connecting nipple 12. These tubular portions and nipples form a continuous water space, which communicates with the hollow interior of each of the units. Above the abutting flanges 10, the horizontal header 7^b of each section has a centrally arranged nipple seat 13, these seats receiving the connecting nipples 14, which form a continuous water or steam chamber 15 at the top of the structure. 16 designates two return connections which communicate with the continuous water space, and 17 designates outlet connections from the space 15 for the heated water or steam. Obviously, however, I may employ but one intake and offtake connection or any desired number of these connections.

As will be readily understood from the drawings, when the sections or units are assembled, they form a plurality of adjacent vertical water legs connected at top and bottom, and each of them separated by a tortuous passage from the opposing surface of an adjacent section or sections. These tortuous passages are for the flames and other products of combustion from the burners 18, which extend within the lower portions of

said passages. Where gas is employed as the fuel, this may be supplied by a pipe 19, having a plurality of branches 20, leading into the lower portion of each of the said 5 tortuous passages through openings 21, formed in the bottom flanges 9 of the sections. Each branch 20 has a plurality of burners, branched at their ends, as shown at 22. Each branch 22 is preferably ar- 10 ranged to direct a flame against an upwardly converging surface 23 of the lower portion of an adjacent unit. These upwardly converging surfaces define the main combustion chamber portions of the tortu- 15 ous passage and also form contracted lower portions of the water legs. Some of the burners may be connected to a separate gas supply pipe 19^a to act as pilots.

By this construction, a comparatively 20 large combustion area is provided, while at the same time the lower portions of the water legs, which contain the colder water, are so contracted as to contain at those portions only a relatively small volume. Above 25 the upwardly converging surfaces 23, the tortuous passages are preferably of substantially equal cross sectional area. Preferably the projecting portions of the sections are made long enough so that they project 30 beyond the joints between adjacent sections and form a positive overlap which increases the tortuosity of the passages. It will be noted that the hollow projections of the sections have the inner and outer surfaces of 35 their upper and lower walls sloped in a converging direction. This is a feature of importance for several reasons. In the first place it greatly facilitates the upward circulation of the water in the sections, since 40 it prevents any pocketing of hot water or steam such as would occur if these surfaces were horizontal. In the second place it greatly facilitates the dislodgment of any soot or other products of combustion which 45 may stick upon the upper and outer surfaces of said projections. Furthermore, it enables the sections to be readily cast, the slope of the projection being sufficient to give proper draft in molding.

50 The abutting flanges 10 form the top of these tortuous passages, but are cut away vertically at the front end of the heater, as shown at 24 in Figs. 2, 3, and 4, to provide flues through which the products of combustion pass upwardly between the webs of the units into the upper chamber 25 below the horizontal headers. This chamber 25 is 55 a continuous chamber except for the connections 26 which connect the horizontal headers to the webs of the units and which extend therethrough and are completely surrounded by said chamber. The vertical header of one or more of the sections are cut away at the back to provide the outlet 27, 60 which leads into the smoke box 28. This

smoke box may be bolted to the sections, as indicated at 29 in Fig. 2. I preferably form it in two sections having an oblique joint at 30, and the outer section 28^a being reversible so that its offtake connection 31 70 may be directed either vertically, as shown in full lines in Fig. 3, or horizontally, as shown in dotted lines in said figure. 32 designates doors by means of which access may be had to the burners, the chamber 25 75 and the flues between the headers. These doors are preferably provided with peep holes 33, having closures 34 of mica or other suitable material.

My invention provides a heater or boiler 80 which is simple in its construction, the sections or units being of a form which can readily be cast and also capable of being readily assembled. The shape of the sections or units, whereby tortuous passages for 85 the products of combustion are provided not only increases the vertical distance through which such products of combustion must travel before escaping, but also largely increases the heating area of the sections di- 90 rectly exposed to the action of such products. This makes a very economical heater or boiler, in which a maximum heating effect can be obtained with a minimum of fuel.

It will be obvious that instead of the specific arrangement of burners which I have have shown and described, various other forms and arrangements of burners may be used; that the shape of the tortuous passages 100 may be widely varied, and that other changes may be made within the scope of the appended claims.

I claim:

1. A section or unit for sectional heaters 105 or boilers, comprising a hollow vertical web portion formed at each of its vertical sides with hollow projections extending horizontally of the section from front to rear, some of the projections on the two sides being 110 staggered with respect to each other, and the staggered projections having their upper, inner and outer surfaces sloped downwardly and outwardly and the lower inner and outer surfaces thereof being sloped upwardly and outwardly, said sections also having other horizontal projections, one on each side, above the staggered projections and which are horizontally opposite each other, each of said other projections having 115 a vertical opening therethrough near the front edge of the section; substantially as described.

2. A sectional heater or boiler, comprising a plurality of spaced hollow projections 125 or units which extend from the back to the front of the heater, each of said units having a hollow vertical web portion formed on both sides with hollow projections which extend horizontally from front to rear, some 130

of the projections of each section being staggered with respect to adjacent projections, and each upper projection being abutted against the corresponding projection 5 of an adjacent section, said abutting projections closing the upper portions of the flue spaces between adjacent sections and forming horizontal flues leading from the front to the back of the heater, the abutting projections having vertical flue openings there-through near the front of the heater, the projections also having rearwardly extending flue spaces above the abutting projections and with which said openings communicate, and a stack connection with which 10 said flue spaces communicate at their rear ends; substantially as described.

3. A sectional heater or boiler, comprising a plurality of spaced hollow projections or 20 units which extend from the back to the front of the heater, each of said units having a hollow vertical web portion formed on both sides with hollow projections which extend horizontally from front to rear, some 25 of the projections of each section being staggered with respect to adjacent projections, and each upper projection being abutted against the corresponding projection of an adjacent section, said abutting 30 projections closing the upper portions of the flue spaces between adjacent sections and forming horizontal flues leading from the front to the back of the heater, the abutting projections having vertical flue openings 35 therethrough near the front of the heater, the projections also having rearwardly extending flue spaces above the abutting projections and with which said openings communicate, and a stack connection with which 40 said flue spaces communicate at their rear ends, said projections having their upper surfaces sloped downwardly and their lower faces sloped upwardly; substantially as described.

45 4. A sectional heater or boiler, comprising a plurality of spaced hollow projections or units which extend from the back to the front of the heater, each of said units having a hollow vertical web portion formed on 50 both sides with hollow projections which extend horizontally from front to rear, some of the projections of each section being staggered with respect to adjacent projections, and each upper projection being 55 abutted against the corresponding projec-

tion of an adjacent section, said abutting projections closing the upper portions of the flue spaces between adjacent sections and forming horizontal flues leading from the front to the back of the heater, the abutting 60 projections having vertical flue openings therethrough near the front of the heater, the projections also having rearwardly extending flue spaces above the abutting projections and with which said openings communicate, and a stack connection with which 65 said flue spaces communicate at their rear ends, said projections having their upper surfaces sloped downwardly and their lower faces sloped upwardly, and each of said 70 sections being narrowed at its lower portion, thereby forming between their lower portions enlarged combustion chambers at the lower portions of the flue spaces between the sections, and gas burners extending into 75 said chambers; substantially as described.

5. A heater or boiler comprising end sections and intermediate sections, there being circulating connections between said sections as well as inlet and outlet connections, 80 each of said sections having a hollow vertical header and a hollow vertical web communicating at one end with the header, one side of the web of each of the end sections being provided with hollow horizontal projections extending from one end of the section to the header, the intermediate sections having hollow projections on each side of its web extending from one end to the header, the hollow projections on the one 85 section being staggered with relation to the projections on the other section to form circuitous passages between the sections which are open at one end and closed at the other end by the headers, there being a combustion chamber in the lower portion of each circuitous passage, an off-take flue, communications between the upper end of each circuitous passage and the off-take flue, and a door for closing the open end of each circuitous passage and the combustion chamber between adjacent headers, substantially as 90 described.

95 In testimony whereof, I have hereunto set my hand.

ALEXANDER H. MORROW.
